INVENTOR.

A. W. BOTCHER
BY *Victor J. Evans*
ATTORNEY.

UNITED STATES PATENT OFFICE.

ALBERT W. BOTCHER, OF SAN FRANCISCO, CALIFORNIA.

DRAPERY STRETCHING AND CUTTING DEVICE.

Application filed November 22, 1924 Serial No. 751,634.

To all whom it may concern:

Be it known that I, ALBERT W. BOTCHER, a citizen of the United States, residing at San Francisco, in the county of San Francisco and State of California, have invented new and useful Improvements in Drapery Stretching and Cutting Devices, of which the following is a specification.

This invention relates to improvements in 10 drapery stretching and cutting devices.

The principal object of this invention is to provide means for holding fabrics during the measuring and cutting operation.

Another object is to produce a device of 15 this character which may be attached to the ordinary cutting table without altering the construction of the table.

Another object is to produce a device which may be accommodated to any width 20 of table.

A still further object is to produce a device of this character which is cheap to manufacture and simple to operate.

Other objects and advantages will be ap- 25 parent during the course of the following description.

In the accompanying drawings forming a part of this specification and in which like numerals are employed to designate like 30 parts throughout the same,

Figure I is a top plan view of a table constructed in accordance with my invention,

Figure II is a fragmentary detail view 35 showing my device attached to one end of the table,

Figure III is a plan view of one of the holding elements, and

Figure IV is a fragmentary detail view 40 showing the manner of holding the fabric.

In the laying out of curtains and drapes it is essential that the material be cut evenly in order that the drape will hang properly.

At the present time it is customary to lay the 45 goods upon a table and cut the same with a pair of shears using the eye or a drawn thread as the means for making an even cut. It is my intention to provide means whereby the material may be properly held so that it will be evenly stretched throughout 50 its length and to then cut along a given guide, thus making an even cut or fold.

In the accompanying drawings wherein for the purpose of illustration is shown a 55 preferred embodiment of my invention, the numeral 5 designates the top of a table upon

which my device is slidably attached. As the two parts of my device located at opposite ends of the table are identical, but one will be described.

Referring to Figure I, it will be noted that at 6 and 7 I have provided channel members which engage the sides of the table. These channel members are connected by a cross piece 8. Secured to each of these channel members is an upstanding support 9, within which are detachably secured rods 11 and 12. The rod 11 serves to pivotally support a plurality of holding elements 13 which are preferably formed of sheet metal 70 and have an eye 14, through which the rod 11 passes.

The free end of these holding elements are provided with teeth 15, which teeth when brought into engagement with a fabric 16, 75 as shown in Figure IV, serve to retain the edge of the fabric against the cross piece 8.

By referring to Figure I, it will be seen that there are a plurality of these holding elements placed upon the rod 11, which construction permits the accommodation of my device to tables of varying widths, and by further referring to Figure II, it will be noted that these holding elements may be swung to the dotted line position of this 80 figure so as to allow for the adjusting of the material previous to the holding operation. After the material has been properly adjusted, shears may be employed or a knife used to cut along the cross piece 8, using the 90 same as a guide.

The manner of operating my device is as follows:—

The channel members 6 and 7 together with their associated parts are slid upon the table and are held against movement by a cam latch 10 pivoted beneath each of the channel members. It is obvious that any form of latch mechanism may be employed. One of these devices is positioned on each 100 end of the table, after which the holding elements are moved to the dotted line position of Figure II, the goods to be cut is passed beneath the rods 11 and 12 until the edge abuts the cross piece 8, the holding elements are dropped, the goods carried to the opposite end of the table and passed beneath the rods 11 and 12, over the cross piece 8 and smoothed out, after which operation the holding elements 13 at this end 105 of the table are dropped into contact with the goods. The cutters can then sever the

goods at any point desired, preferably using the cross piece 8 as a guide.

It will accordingly be seen that I have provided a device which will enable an operator to make an even cut in a minimum amount of time.

It is to be understood that the form of my invention herewith shown and described is to be taken as a preferred example of the same, and that various changes in the shape, size and arrangement of parts may be resorted to without departing from the spirit of the invention or the scope of the subjoined claim.

15 Having thus described my invention, I claim:—

In a device of the character described adapted to be attached to a table, a pair of channel members adapted to engage the opposite sides of a table, a cross piece extending between said channel members, supports mounted on said channel members, a rod extending between said supports, a plurality of holding elements pivotally supported on said rod, said holding elements having a plurality of fabric engaging points, and a second rod extending between said supports for the purpose of retaining said holding elements in inoperative position.

In testimony whereof I affix my signature.

ALBERT W. BOTCHER.
